UNITED STATES PATENT OFFICE.

IRENE DESY, OF LEWISTOWN, MONTANA, ASSIGNOR OF ONE-FOURTH TO DANIEL M. CROWLEY AND ONE-FOURTH TO GEORGE M. STONE, OF LEWISTOWN, MONTANA.

SULKY-PLOW.

No. 839,122.

Specification of Letters Patent.

Patented Dec. 25, 1906.

Application filed October 4, 1905. Serial No. 281,292.

To all whom it may concern:

Be it known that I, IRENE DESY, a citizen of the United States, residing at Lewistown, in the county of Fergus and State of Montana, have invented new and useful Improvements in Sulky-Plows, of which the following is a specification.

This invention has relation to sulky-plows equipped with a plurality of plows—that is, furrow forming and turning means—and other various necessary appliances.

It is the object of my invention to provide improvements in the class of plows mentioned that will render the same more efficient and more easily operated and controlled than plows of the same type as heretofore constructed.

To these ends my invention consists of various improvements having in view the lessening of the draft, the perfect turning of the ground, especially sod, and a construction whereby the same number of horses can plow or break ground to a much greater width than heretofore, and the provision of an improved plow-frame and sulky-frame and means whereby the plows and sulky can be raised with greater facility and ease than heretofore, all as will be hereinafter fully described, and subsequently pointed out in the subjoined claims.

In the accompanying drawings, forming a part of this specification, Figure 1 is a perspective view of the invention looking from near the rear toward the front. Fig. 2 is a plan view of the same. Fig. 3 is a sectional view taken in the line 3 3 of Fig. 4. Fig. 4 is a sectional side elevation taken in the plane 4 4 of Fig. 2. Fig. 5 is a sectional detail view taken in the plane of the axis of a disk moldboard and showing the relationship of the latter to the share and colter or sod-cutter. Fig. 6 is a sectional detail view, on an enlarged scale, of parts portrayed in Fig. 3, assisting to show the means for raising and lowering the plow-frames. Fig. 7 is a sectional detail view of fewer parts than is intended to be represented in Fig. 4 with a design to make clear the relationship of the pivotal lever and its connections whereby the plow-frame is raised and lowered.

While the title given to the invention is "sulky-plows" and the specification dis-

cusses it as such, it is to be understood that the invention is not confined to plows of any particular type. So far as the principles of the invention may admit it may be employed as a walking-plow, or parts may be used in different plows if found applicable in other connections without surrender of any rights guaranteed me by law.

In explanation of the construction and mode of operation of the improvements effected by me let *a* represent the sulky-frame, which is constructed of parallel side bars offset and widened at a point substantially where the supporting-wheel *b* is met, connected at their forward ends by a straight bar *c* and at their rear ends by an obliquely-extended bar *d*. A cross-rod *e* assists in bracing or stiffening the sulky-frame laterally at a point where it is subjected to the greatest lateral strain.

The plow-frame is arranged on a lower plane than the sulky-frame and consists of the central draft-bar *f*, extending from the front end, where the draft-clevis is attached, to the rear, where it is given a recurvate bend downward and forward to near the ground. The said draft-bar is composed of one piece of steel or similar metal, and the plowshare *g* is attached to the lower rearward end, and a sod-cutter or colter *h* is connected with the landside of the plow. The share has a V-shaped notch formed in its rear end, and the edge of the rotary moldboard or furrow-turning disk *i* of each plow is arranged just behind the share, to the left of the V-shaped notch *j*, and with its forward edge substantially in line with the sod-cutter *h*.

Each plow and its adjuncts is connected with a draft-bar *k*, having a recurvate bend at its rear end, like the central draft-bar, and is arranged laterally of the latter bar and parallel with it and connected at its forward end either immediately or meditately through another lateral bar by an angular bend *l*. The lateral bars *k* extend from substantially the line in which the widening offset is formed in the sulky-frame rearwardly to a line substantially coinciding with the plane of the rear connecting-bar of the sulky-frame, so that the line of plows is on an angle with respect to the line of draft, the plow on the extreme right being farthest forward. More-

over, the lateral bars *k* may be arranged on both sides of the central draft-bar in number and order suited to circumstances and convenience. *m* designates obliquely-arranged brace-bars between the lateral bars and central bar to brace and keep said bars in proper place. The arrangement of these brace-bars is such as to enable them to most effectively perform the functions required of them.

- 10 The rotary moldboards or disks are each arranged on an arm *n* of an angular bar, the other arm of which is secured to the recurvate bend of its draft-bar, and the said disks are left to turn or be turned by the friction of the ground thereagainst. The shares are secured to the ends of the draft-bars, which latter in their bends become substantial standards to the shares and maintain the same in flat order—that is, so as to extend
- 15 parallel with the surface of the ground—and they cut the ground in that order, while the colter cuts it vertically on a line coincident with the inside of the furrow, and the rotary moldboard coming in contact therewith turns it over. This, in connection with other contrivances—as, for instance, the described arrangement of the rotary moldboard with respect to the sod-cutter and the rear of the share—makes the plowing and turning of a
- 20 furrow easy, as hereinbefore stated.

An arm *o* is connected at one end to a plow-standard and having the other end free and flattened, which free end extends over the disk and in close proximity to the face of the disk, so as to scrape off or remove the adhering ground or refuse therefrom.

- 25 *p* designates an overbar having right-angular slotted and curved ends *r* depending therefrom, which are secured to the side bars of the sulky-frame. A bar *s* below the overbar passes loosely through holes formed in pieces *t*, connected at their lower ends with the draft-bars, and the gudgeons at the end of the said bar *s* extend into the slots of the curved ends or arms *r* of the overbar *p*. Toggle-levers *u* are connected with the overbar *p* and the bar *s* through the intervention of suitable means—as, for instance, by clips 1, adapted to pivot and slide upon a common bail 2, fixed to said overbar *p*, and by sleeves 3, loosely arranged upon said bar *s* and having pivoted thereto said toggle-levers. A pair of rods *v*, standing apart at their lower ends and pivoted upon the bar *s* at said ends, are brought together at their upper ends and pivoted upon the forward end of a curved lever *w*, which is fulcrumed upon suitable means on the upper side of the overbar.

j' is a sulky-seat secured on the upper end of a spring-bar *j''* and attached at its lower end to the sulky-frame. (See Fig. 1.) At the right-hand side of the seat is a lever *w* for raising and lowering the plow-frame in the sulky-frame. The said lever *w* is fulcrumed near its center between a standard

*p*², extending up from the overbar *p*, and the upper end *p*³ of a brace-bar *p*⁴, formed similarly to the standard *p*². In Fig. 7 the standard *p*² is of exactly the same form as the part *p*³ and is just beyond the standard *p*³, so that it is not seen. The brace-bar *p*⁴ extends rearwardly and downwardly and is attached at its rear end to the sulky-frame. The lever *w* is provided at its forward end with a downward extension in the form of an arm *w'*, which is provided with numerous holes *w*⁵, adapting it to be adjustably pivoted to the converging ends of the rods *v*, secured through the means shown to the sulky-frame. By operating the lever *w* on its fulcrum its pivotal connection at its front end with the sulky-frame will permit of raising and lowering the plow-frame, as will be readily understood.

x is a toothed segment, the upper end of which is supported from the overbar *p*, and its lower end is secured to the outside of the brace-bar *p*⁴. The lever *w* has a detent or dog *y* operating in bearings on its outside, the inner end of which detent is adapted to engage the peripheral notches *x'* of the segment, and thus provide for holding the lever in any position to which it may be moved. A wire *z* connects the handle *a'* with said dog for its actuation, which handle *a'* is arranged closely to the handle *w*³ of the lever *w*, so that when the operator takes hold of the lever-handle *w*³ to work it he may likewise take hold of the handle *a'* and manipulate it and the dog *y*. By the means last described it will be seen that as said lever *w* is suitably operated the plows and plow-frame may be raised and lowered at will with respect to the sulky-frame, so that the implement as a whole may be taken upon the road or elsewhere from place to place without having the plows come into contact with the ground.

b' designates a lever fulcrumed upon the frame A, as at *c*², and pivotally connected to the arm *c'*, projecting up from the axle of the wheel *b*, and *e'* designates an externally-toothed arcuate bar connected at one end with the overbar and sulky-frame, with which a dog *f'* is adapted to engage and hold the lever *b'* in adjusted position, said dog being connected with a handle *g'* in close proximity to the handle *b'*, so that the dog *f'* may be manipulated substantially as the dog *y* of the lever *w*.

A standard *h''* extends vertically upward from the center of the dual lever *h'*, and to said standard is adjustably connected the outer end of a rod *z'*, the inner end of which is connected to the inner and downward extension *w*² of the lever *w*. A wire rod *z*², having a spring *w*⁵ connected therewith, is attached at one end to the vertical lug *w*⁴ on the lever *w*, and the rod *z*² acts to draw the lever in the direction indicated by the arrow and to depress the inner end of the dual lever

h'. The operator with his feet on the dual lever may actuate it as desired against the stress of other means, and so raise or lower the plow-frame the same as by operating the lever w, all as will be understood by an inspection of Fig. 7.

Guide or caster wheels l' m' have their axle-supports n' passing pivotally through lateral extensions o' of the sulky-frame, and a rod 10 p' effects connection between crank-arms q² q³, forming upper end terminals of said caster-wheel supports n', respectively. A manually-actuated lever q³ has its forward end suitably connected, preferably as shown, 15 to the arm q² of the forward caster or guide wheel and extends rearward, terminating conveniently to the driver's seat j' for actuation in suitably guiding the movement of the machine.

20 An arm n is connected at one of its ends to the side of each draft-bar at the point of its recurvate bend and is rounded at its other or free end. The said arm is bent angularly around the rear edge of the draft-bar and 25 projects into a tubular bearing from the center of the back of the disk i, as shown in Fig. 5, by which means the disk is maintained in place, as hereinbefore described.

The head of the implement will be provided with suitable means for attaching and 30 adjusting the draft-clevis and other necessary means.

I claim—

1. In a sulky-plow, the combination, with 35 the plow-frame, the supporting-wheel and its crank-axle of the sulky-frame comprising parallel side bars, brought closer together at their forward portions, and offset and widened rearwardly from a point substantially where the supporting-wheel is located, 40 the rearward part of the crank-axle being formed as a brace-rod extending from one side bar to the other, a notched segment connected at one end to the crank-axle and at the other end to the sulky-frame, a lever provided with a dog disposed to engage the 45 notches of the segment, the said lever fulcrumed on one of the side bars, a link connecting the forward end of the lever with the 50 crank-axle, the plow-frame carrying the plow-beams, shares and moldboards, hung in the sulky-frame, the construction being such that the raising and lowering of the said 55 lever will raise and lower both the plow-frame and the sulky-frame.

2. In a sulky-plow, the combination, with 60 the plow-frame, carrying the plow-beams, the shares and rotary moldboards, of the sulky-frame comprising parallel side bars, front and end bars, an overbar having right-angular curved and slotted ends extending down and secured to the said side bars, a lower bar connected to the plow-frame and having gudgeons at its ends adapted to operate in the slots of the angular 65 ends of the overbar, toggle-levers intermediate of the said bars, and means connecting the toggle-levers with the bars, and a lever

overbar, a notched segment secured rigidly on the overbar, a lever fulcrumed on the overbar, connected at its forward end with the lower bar, and carrying a dog to engage the notches of the said segment, whereby the 70 plow-frame may be raised and lowered with respect to the sulky-frame.

3. A plow-frame, combined with a sulky-plow frame, the latter arranged above the former, an overbar having curved slotted 75 end portions bent at a right angle to the center and secured to the sides of the sulky-frame, a lower bar connected with the plow-frame and having the gudgeons at its ends adapted to operate in the slots of the angular 80 ends of the overbar, and means connected with the lower bar and the overbar to raise and lower the former and the plow-frame connected with it.

4. A plow-frame, combined with a sulky-plow frame, the latter arranged above the former, an overbar having curved slotted 85 end portions bent at a right angle to the center and secured to the sides of the sulky-frame, a lower bar connected with the plow-frame and having the gudgeons at its ends 90 adapted to operate in the slots of the angular ends of the overbar, toggle-levers intermediate of the said bars, and means connecting the toggle-levers with the bars, and a lever 95 fulcrumed on the overbar and having connections with the lower bar for raising and lowering the latter and the plow-frame.

5. A plow-frame, combined with a sulky-plow frame, the latter arranged above the former, an overbar having curved slotted 100 end portions bent at a right angle to the center and secured to the sides of the sulky-frame, a lower bar connected with the plow-frame and having the gudgeons at its ends 105 adapted to operate in the slots of the angular ends of the overbar, toggle-levers intermediate of the said bars, and means connecting the toggle-levers with the bars, and a lever 110 fulcrumed on the overbar and having connections with the lower bar for raising and lowering the latter and the plow-frame, and an additional dual lever fulcrumed at its center upon the sulky-frame, provided at its ends with means for depressing it by the foot 115 of the operator and connected with the first-mentioned lever, whereby said lever may be operated without employing a hand for that purpose.

6. A plow-frame, combined with a sulky-plow frame, the latter arranged above the former, an overbar having curved slotted 120 end portions bent at a right angle to the center and secured to the sides of the sulky-frame, a lower bar connected with the plow-frame and having the gudgeons at its ends 125 adapted to operate in the slots of the angular ends of the overbar, toggle-levers intermediate of the said bars, and means connecting the toggle-levers with the bars, and a lever 130

fulcrumed on the overbar and having connections with the lower bar for raising and lowering the latter and the plow-frame, a counterbalancing-spring for the plow-frame connected with the lever, and means for latching the lever in any position to which it may be moved.

7. A plow-frame, combined with a sulky-plow frame, the latter arranged above the former, an overbar having curved slotted end portions bent at a right angle to the center and secured to the sides of the sulky-frame, a lower bar connected with the plow-frame and having the gudgeons at its ends adapted to operate in the slots of the angular ends of the overbar, and means connected with the lower bar and the overbar to raise and lower the former and the plow-frame connected with it, and a lever fulcrumed on

the sulky-frame to raise it and the plow-frame in unison.

8. A frame for a sulky-plow consisting of parallel side bars, brought closer together at their forward portions, with a right-angular bar connecting their forward ends, and offset near their middle and extended on lines wider apart at their rearward portions, with an angular or oblique bar connecting their rear ends, and an overbar having right-angular curved and slotted ends extending and secured to the sides of the frame.

In testimony whereof I affix my signature in presence of two subscribing witnesses.

IRENE DESY.
